A liquid discharge apparatus includes: liquid channels each including an individual channel having a nozzle, a supply manifold connected to the individual channel to supply liquid to the individual channel, and a return manifold connected to the individual channel, along which the liquid that has not been discharged from the nozzle flows; and bypasses each connected to the supply manifold and the return manifold. The liquid channels include a first liquid channel, a second liquid channel, and a third liquid channel arranged in a first direction. The supply manifold of the first liquid channel is connected via a first bypass of the bypasses, only to the return manifold of the second liquid channel. The return manifold of the first liquid channel is connected via a second bypass of the bypass, only to the supply manifold of the third liquid channel.

LIQUID DISCHARGE APPARATUS

REFERENCE TO RELATED APPLICATIONS

This application claims priority from Japanese Patent Application No. 2021-187626 filed on Nov. 18, 2021. The entire content of the priority application is incorporated herein by reference.

BACKGROUND ART

There is known a liquid discharge apparatus including: a first supply manifold and first return manifold which are connected to a first individual channel; and a second supply manifold and second return manifold which are connected to a second individual channel. The first supply manifold and the second return manifold are connected by a first bypass route. The first individual channel has a first nozzle discharge port, and, due to pressure that has been applied from a piezoelectric body to liquid in the first individual channel, the liquid is discharged from the first nozzle discharge port.

DESCRIPTION

In this kind of liquid discharge apparatus, the first supply manifold is connected to the first return manifold by the first individual channel. A pressure wave that has been applied to the liquid in the first individual channel from the piezoelectric body will propagate to the first supply manifold and will propagate to the first return manifold. Supposing the first supply manifold and the first return manifold to be connected by a bypass route, a wave of large amplitude will be generated as a result that the pressure wave propagating to the first supply manifold and pressure wave propagating to the first return manifold are superimposed in phase via the bypass route. As a result, there will occur crosstalk whereby discharge of the liquid from nozzle discharge ports of surrounding individual channels will become unstable. In contrast, in the above-described liquid discharge apparatus, the first supply manifold is connected to the second return manifold by the first bypass route. As a result, the pressure wave propagating to the first supply manifold and pressure wave propagating to the first return manifold (that is in phase with the pressure wave propagating to the first supply manifold) will not merge, hence crosstalk will be reduced.

However, in the case of the above-described liquid discharge apparatus further including a third supply manifold and a third return manifold which are connected by a third individual channel, the first supply manifold will be connected by bypass routes to the second return manifold and the third return manifold. In contrast, each of the second supply manifold and the third supply manifold will be connected by a bypass route to the first return manifold. In this way, the number of the bypass routes of the first supply manifold will differ from other manifolds, and liquid flow rate in the first supply manifold will differ from in other manifolds. There is a risk that difference in flow rates among the manifolds will cause nonuniformity of head heat-dissipating performance and bubble discharge performance.

The present teaching, which was made in view of such circumstances, has an object of providing a liquid discharge apparatus enabling uniformity of flow rates of liquid in manifolds to be achieved, while crosstalk is reduced.

According to an aspect of the present teaching, there is provided a liquid discharge apparatus including: a plurality of liquid channels each including: an individual channel having a nozzle; a supply manifold connected to the individual channel to supply liquid to the individual channel; and a return manifold connected to the individual channel, the liquid that has not been discharged from the nozzle being flowed through the return manifold; and a plurality of bypasses each connected to the supply manifold and the return manifold to cause the liquid to flow therethrough, wherein the liquid channels include a first liquid channel, a second liquid channel, and a third liquid channel arranged in a first direction, the supply manifold included in the first liquid channel is connected only to the return manifold included in the second liquid channel, via a first bypass included in the bypasses, and the return manifold included in the first liquid channel is connected only to the supply manifold included in the third liquid channel, via a second bypass included in the bypasses.

FIG. 1 is a diagram in which a liquid discharge apparatus according to an embodiment of the present teaching is viewed from above.

FIG. 2 is a cross-sectional view depicting part of a head.

FIG. 3 is a diagram in which a channel unit in the head of FIG. 2 is viewed from above.

FIG. 4 is an exploded view of the channel unit of FIG. 2.

FIG. 5 is a perspective view of the channel unit of FIG. 2.

FIGS. 6A to 6C are diagrams in which a liquid discharge apparatus according to a second modification of the present teaching is viewed from the left.

FIG. 7 is a diagram in which a channel unit of a liquid discharge apparatus according to a fourth modification of the present teaching is viewed from above.

FIG. 8 is a perspective view of the channel unit of FIG. 7.

FIG. 9 is a perspective view of a channel unit of a liquid discharge apparatus according to a fifth modification of the present teaching.

FIGS. 10A and 10B are diagrams in which the channel unit of FIG. 9 is viewed from the left.

FIG. 11 is a perspective view of a channel unit of a liquid discharge apparatus according to a sixth modification of the present teaching.

FIG. 12 is a diagram in which a channel unit of a liquid discharge apparatus according to another modification of the present teaching is viewed from the left.

FIG. 13 is a diagram in which a channel unit of a liquid discharge apparatus according to still another modification of the present teaching is viewed from the left.

An embodiment of the present teaching will be specifically described below with reference to the drawings. Note that hereafter, identical or corresponding elements will be assigned with identical reference symbols in all of the drawings, and duplicated descriptions thereof omitted.

<Liquid Discharge Apparatus>

A liquid discharge apparatus 10 according to one embodiment of the present teaching is a device that discharges liquid such as ink, as depicted in FIG. 1. Although hereafter, there will be described an example of the liquid discharge apparatus 10 having been applied to an ink jet printer in which an image is formed by liquid being discharged onto a recorded medium A from a head 20, the liquid discharge apparatus 10 is not limited to this. Moreover, a sheet material of the likes of paper and cloth may be employed as the recorded medium A.

The liquid discharge apparatus 10, in which a line head system is adopted, comprises a platen 11, a head unit 12, a storage tank 13, a conveying device 17, and a control unit 14. Note that a designated first direction will be referred to as a front-rear direction, a second direction intersecting with

(for example, orthogonal to) the first direction will be referred to as a left-right direction, and a third direction intersecting with (for example, orthogonal to) the first direction and the second direction will be referred to as an up-down direction. However, disposition of the liquid discharge apparatus 10 is not limited to this.

The platen 11, which is of a rectangular flat plate-like shape, for example, has a flat upper surface on which the recorded medium A is placed, and determines a distance between the recorded medium A and the head 20 in the up-down direction. The head 20, which extends longways in the left-right direction, has a length in the left-right direction not less than that of the recorded medium A. The head unit 12 is provided with one or a plurality of the heads 20. The head 20 is provided with a discharge surface 21 (FIG. 2) facing the upper surface of the platen 11, and a plurality of nozzles 31 that open onto the discharge surface 21. Note that details of the head 20 will be mentioned later.

The storage tank 13 is provided for each kind of liquid. For example, four storage tanks 13 have respectively stored therein black, yellow, cyan, and magenta liquids. The storage tanks 13 are corresponded to the plurality of nozzles 31 of the head 20, and supply liquid to the corresponding nozzles 31.

The conveying device 17 has a pair of conveying rollers 18 and conveying motors 19, for example. The pair of conveying rollers 18 are disposed sandwiching the platen 11 between each other in the front-rear direction with their axes extending in the left-right direction. The conveying roller 18, which is coupled to the conveying motor 19, rotates around its axis due to the conveying motor 19. As a result, the recorded medium A is conveyed in the front-rear direction on the platen 11.

The control unit 14, which is a computer, comprises an arithmetic circuit such as a CPU, and a memory of the likes of RAM and ROM. In the control unit 14, an arithmetic unit controls operation of the conveying motor 19 of the conveying device 17 and drive element 23 of the head 20, based on a program stored in a storage unit. For example, the control unit 14 executes a discharging operation causing liquid to be discharged onto the recorded medium A from the head 20 by the drive element 23, and a conveying operation causing the recorded medium A to be conveyed by the conveying device 17. As a result, there proceeds a print processing in which an image is formed on the recorded medium A by liquid, without the head 20 moving.

<Head>

As depicted in FIGS. 2 and 3, the head 20 comprises a channel forming body 22 and the drive element 23, and is installed with a sub-tank 15. The channel forming body 22 is a laminated body having laminated therein a plurality of plates, and includes a nozzle plate 24, a plurality of (for example, eight) channel plates 25, and a vibrating plate 26, for example. These plates, which are of rectangular plate-like shape, are laminated in the up-down direction in this order, and are bonded to each other by an adhesive agent, or the like.

Each plate has formed therein a through-hole penetrating the plate, and a recess recessing from a lower surface or upper surface of the plate. For example, the plate comprises a resin or metal, and has its through-hole and recess formed by etching. Inside the channel forming body 22 where each of the plates are laminated, the through-holes and recesses are combined to form a channel unit 27, for example. The channel unit 27 includes a plurality of liquid channels 28 and a plurality of bypasses 60. The liquid channel 28 includes a plurality of individual channels 30, a supply manifold 40,

and a return manifold 50. The bypass 60 connects the supply manifold 40 and the return manifold 50, and has liquid flowing therethrough. Note that details of the manifolds and bypasses 60 will be mentioned later.

As depicted in FIG. 2, the individual channel 30 includes the nozzle 31, a supply throttle 32, a pressure chamber 33, a descender 34, and a return throttle 35. The nozzle 31 penetrates the nozzle plate 24 in the up-down direction, and opens onto the discharge surface 21 being the lower surface of the nozzle plate 24. The supply throttle 32 is connected to the supply manifold 40 and pressure chamber 33. Cross-sectional area orthogonal to a flow-through direction that liquid flows in these is smaller in the supply throttle 32 than in the supply manifold 40 and the pressure chamber 33. The pressure chamber 33 has its upper end opening covered by the vibrating plate 26. The descender 34 is connected to the pressure chamber 33 and the nozzle 31. The return throttle 35 is connected to the descender 34 and return manifold 50, and cross-sectional area orthogonal to a flow-through direction that liquid flows is smaller in the return throttle 35 than in the descender 34 and the return manifold 50.

The drive element 23, which is an element applying a discharge pressure to liquid of the pressure chamber 33, is, for example, a piezoelectric element. The drive element 23 expands/contracts on receiving a control signal from the control unit 14 (FIG. 1). The vibrating plate 26 between the drive element 23 and the pressure chamber 33 deforms cooperatively with the drive element 23, and undergoes change in a direction that will increase/decrease volume of the pressure chamber 33. Hence, liquid of the pressure chamber 33 is applied with a discharge pressure discharging it from the nozzle 31, and liquid is discharged from the nozzle 31 communicating with the pressure chamber 33.

<Manifolds and Bypasses>

As depicted in FIG. 3, the supply manifold 40 and the return manifold 50, which extend longways in the left-right direction, are connected to a plurality of the individual channels 30. For example, the supply manifold 40 has a supply port 41 at its right end, and an outflow port 42 at its left end. The return manifold 50 has a return port 51 at its right end, and an inflow port 52 at its left end. The supply port 41 is connected to the sub-tank 15 by a supply pipe 43, and the return port 51 is connected to the sub-tank 15 by a return pipe 44. Moreover, the outflow port 42 and the inflow port 52 are connected by the bypass 60. The sub-tank 15 is connected by a tube 13a (FIG. 1) to the storage tank 13.

The plurality of liquid channels 28 include a first liquid channel 28a, a second liquid channel 28b, and a third liquid channel 28c that are arranged in the front-rear direction. The first liquid channel 28a includes a first supply manifold 40a being the supply manifold 40 and first return manifold 50a being the return manifold 50, and a plurality of first individual channels 30a being the individual channels 30 connected to these first supply manifold 40a and first return manifold 50a. The second liquid channel 28b includes a second supply manifold 40b being the supply manifold 40 and second return manifold 50b being the return manifold 50, and a plurality of second individual channels 30b being the individual channels 30 connected to these second supply manifold 40b and second return manifold 50b. The third liquid channel 28c includes a third supply manifold 40c being the supply manifold 40 and third return manifold 50c being the return manifold 50, and a plurality of third individual channels 30c being the individual channels 30 connected to these third supply manifold 40c and third return manifold 50c.

The first supply manifold **40a**, the second supply manifold **40b**, and the third supply manifold **40c** are arranged in this order from the rear. The first return manifold **50a**, the second return manifold **50b**, and the third return manifold **50c** are arranged in this order from the rear. The first supply manifold **40a** is disposed above the first return manifold **50a** so as to overlap the first return manifold **50a** viewing along the up-down direction. The second supply manifold **40b** is disposed above the second return manifold **50b** so as to overlap the second return manifold **50b** viewing along the up-down direction. The third supply manifold **40c** is disposed above the third return manifold **50c** so as to overlap the third return manifold **50c** viewing along the up-down direction.

The bypass **60** includes a first bypass **61**, a second bypass **62**, and a third bypass **63**. The first bypass **61** is connected to the outflow port **42** of the first supply manifold **40a** and the inflow port **52** of the second return manifold **50b**. The second bypass **62** is connected to the outflow port **42** of the third supply manifold **40c** and the inflow port **52** of the first return manifold **50a**. The third bypass **63** is connected to the outflow port **42** of the second supply manifold **40b** and the inflow port **52** of the third return manifold **50c**.

As depicted in FIG. 4, the plurality of channel plates **25** in the channel forming body **22** include a first channel plate **25a**, a second channel plate **25b**, a third channel plate **25c**, and a fourth channel plate **25d**. The first channel plate **25a**, the second channel plate **25b**, the third channel plate **25c**, and the fourth channel plate **25d** are laminated from above in this order. For example, in the up-down direction, dimensions of the first channel plate **25a** and fourth channel plate **25d** are larger than dimensions of the second channel plate **25b** and third channel plate **25c**. Note that in FIG. 4, the individual channel **30** is not illustrated.

The first supply manifold **40a**, the second supply manifold **40b**, and the third supply manifold **40c** are formed as through-holes penetrating the first channel plate **25a** in the up-down direction, and extend in the left-right direction. The first return manifold **50a**, the second return manifold **50b**, and the third return manifold **50c** are formed as through-holes penetrating the fourth channel plate **25d** in the up-down direction, and extend in the left-right direction.

The first bypass **61** includes a first upper portion **61a**, a first middle portion **61b**, and a first lower portion **61c**, these being connected in this order. The first upper portion **61a** penetrates the second channel plate **25b** in the up-down direction. In the front-rear direction, a dimension of the first upper portion **61a** is larger than a dimension of the first supply manifold **40a**, and the first upper portion **61a** extends further to the front than the first supply manifold **40a**. The first upper portion **61a** overlaps the first supply manifold **40a** viewing along the up-down direction, and an upper end of the first upper portion **61a** is connected to the outflow port **42** at a lower end of the first supply manifold **40a**. The first middle portion **61b** penetrates the third channel plate **25c** in the up-down direction. The first lower portion **61c** penetrates the fourth channel plate **25d** in the up-down direction. In the front-rear direction, a dimension of the first lower portion **61c** is larger than a dimension of the second return manifold **50b**, and the first lower portion **61c** extends further to the rear than the second return manifold **50b**. In a portion where the first upper portion **61a** and the first lower portion **61c** overlap when viewed along the up-down direction, an upper end of the first middle portion **61b** is connected to a lower end of the first upper portion **61a**, and a lower end of the first middle portion **61b** is connected to an upper end of the first

lower portion **61c**. A front end of the first lower portion **61c** is connected to the inflow port **52** being a rear end of the second return manifold **50b**.

The second bypass **62** includes a second upper portion **62a**, a second middle portion **62b**, and a second lower portion **62c**, these being connected in this order. The second upper portion **62a** penetrates the second channel plate **25b** in the up-down direction. In the front-rear direction, a dimension of the second upper portion **62a** is larger than a dimension of the third supply manifold **40c**, and the second upper portion **62a** extends further to the rear than the third supply manifold **40c**. The second upper portion **62a** overlaps the third supply manifold **40c** viewing along the up-down direction, and an upper end of the second upper portion **62a** is connected to the outflow port **42** at a lower end of the third supply manifold **40c**. The second middle portion **62b** penetrates the third channel plate **25c** in the up-down direction. The second lower portion **62c** penetrates the fourth channel plate **25d** in the up-down direction. In the front-rear direction, a dimension of the second lower portion **62c** is larger than a dimension of the first return manifold **50a**, and the second lower portion **62c** extends further to the front than the first return manifold **50a**. In a portion where the second upper portion **62a** and the second lower portion **62c** overlap when viewed along the up-down direction, an upper end of the second middle portion **62b** is connected to a lower end of the second upper portion **62a**, and a lower end of the second middle portion **62b** is connected to an upper end of the second lower portion **62c**. A rear end of the second lower portion **62c** is connected to the inflow port **52** being a front end of the first return manifold **50a**.

The third bypass **63** includes a third upper portion **63a**, a third middle portion **63b**, and a third lower portion **63c**, these being connected in this order. The third upper portion **63a** penetrates the second channel plate **25b** in the up-down direction. In the front-rear direction, a dimension of the third upper portion **63a** is larger than a dimension of the second supply manifold **40b**, and the third upper portion **63a** extends further to the front than the second supply manifold **40b**. The third upper portion **63a** overlaps the second supply manifold **40b** viewing along the up-down direction, and an upper end of the third upper portion **63a** is connected to the outflow port **42** at a lower end of the second supply manifold **40b**. The third middle portion **63b** penetrates the third channel plate **25c** in the up-down direction. The third lower portion **63c** penetrates the fourth channel plate **25d** in the up-down direction. In the front-rear direction, a dimension of the third lower portion **63c** is larger than a dimension of the third return manifold **50c**, and the third lower portion **63c** extends further to the rear than the third return manifold **50c**. In a portion where the third upper portion **63a** and the third lower portion **63c** overlap when viewed along the up-down direction, an upper end of the third middle portion **63b** is connected to a lower end of the third upper portion **63a**, and a lower end of the third middle portion **63b** is connected to an upper end of the third lower portion **63c**. A front end of the third lower portion **63c** is connected to the inflow port **52** being a rear end of the third return manifold **50c**.

As depicted in FIG. 5, the first supply manifold **40a** included in the first liquid channel **28a** is connected via the first bypass **61** included in the bypass **60**, only to the second return manifold **50b** included in the second liquid channel **28b**. The first return manifold **50a** included in the first liquid channel **28a** is connected via the second bypass **62** included in the bypass **60**, only to the third supply manifold **40c** included in the third liquid channel **28c**. The second supply manifold **40b** included in the second liquid channel **28b** is

connected via the third bypass 63 included in the bypass 60, only to the third return manifold 50c included in the third liquid channel 28c. Note that in FIG. 5, the individual channel 30 is not illustrated.

<Flow of Liquid>

Liquid is supplied to the sub-tank 15 from the storage tank 13, passes along the supply pipe 43 from the sub-tank 15, and flows into the first supply manifold 40a via the supply port 41. Then, the liquid flows to the left along the first supply manifold 40a, and, while doing so, is supplied to each of the plurality of first individual channels 30a connected to the first supply manifold 40a. In the first individual channel 30a, the liquid flows through the supply throttle 32, the pressure chamber 33, and the descender 34, and is supplied to the nozzle 31. Now, the liquid is discharged from the nozzle 31 upon being applied with a pressure by the drive element 23. On the other hand, liquid that has not been discharged from the nozzle 31 passes through the return throttle 35 and flows into the first return manifold 50a. The liquid flows to the right along the first return manifold 50a, passes along the return pipe 44 from the return port 51 of the first return manifold 50a, and returns to the sub-tank 15. Thus, as a nozzle circulation, the liquid circulates from the sub-tank 15, through the first supply manifold 40a, first individual channels 30a, and first return manifold 50a, back to the sub-tank 15.

Moreover, liquid that has not flowed into the first individual channels 30a from the first supply manifold 40a while flowing to the left along the first supply manifold 40a passes through the first bypass 61 from the outflow port 42 of the first supply manifold 40a, and flows via the inflow port 52 into the second return manifold 50b. The liquid flows to the right along the second return manifold 50b, passes through the return pipe 44 from the return port 51 of the second return manifold 50b, and returns to the sub-tank 15. Thus, as a manifold circulation, the liquid circulates from the sub-tank 15, through the first supply manifold 40a, first bypass 61, and second return manifold 50b, back to the sub-tank 15.

Similarly to in the first supply manifold 40a, liquid flows into the second supply manifold 40b from the sub-tank 15, and, while flowing along the second supply manifold 40b, is supplied to each of the plurality of second individual channels 30b. In the second individual channel 30b, the liquid is discharged from the nozzle 31 upon being applied with a pressure by the drive element 23. On the other hand, liquid that has not been discharged from the nozzle 31 passes along the second return manifold 50b from the second individual channels 30b, and returns to the sub-tank 15. Thus, as a nozzle circulation, the liquid circulates from the sub-tank 15, through the second supply manifold 40b, second individual channels 30b, and second return manifold 50b, back to the sub-tank 15.

Moreover, liquid that has not flowed into the second individual channels 30b from the second supply manifold 40b passes through the third bypass 63 from the second supply manifold 40b, flows into the third return manifold 50c, and returns to the sub-tank 15 from the third return manifold 50c. Thus, as a manifold circulation, the liquid circulates from the sub-tank 15, through the second supply manifold 40b, third bypass 63, and third return manifold 50c, back to the sub-tank 15.

Similarly to in the first supply manifold 40a, liquid flows into the third supply manifold 40c from the sub-tank 15, and, while flowing along the third supply manifold 40c, is supplied to each of the plurality of third individual channels 30c. In the third individual channel 30c, the liquid is

discharged from the nozzle 31 upon being applied with a pressure by the drive element 23. On the other hand, liquid that has not been discharged from the nozzle 31 passes along the third return manifold 50c from the third individual channels 30c, and returns to the sub-tank 15. Thus, as a nozzle circulation, the liquid circulates from the sub-tank 15, through the third supply manifold 40c, third individual channels 30c, and third return manifold 50c, back to the sub-tank 15.

Moreover, liquid that has not flowed into the third individual channels 30c from the third supply manifold 40c passes through the second bypass 62 from the third supply manifold 40c, flows into the first return manifold 50a, and returns to the sub-tank 15 from the first return manifold 50a. Thus, as a manifold circulation, the liquid circulates from the sub-tank 15, through the third supply manifold 40c, second bypass 62, and first return manifold 50a, back to the sub-tank 15.

Thus, the first supply manifold 40a and the first return manifold 50a of the first liquid channel 28a are connected by bypasses 60 to liquid channels 28 that differ from each other. The second supply manifold 40b and the second return manifold 50b of the second liquid channel 28b are connected by bypasses 60 to liquid channels 28 that differ from each other. The third supply manifold 40c and the third return manifold 50c of the third liquid channel 28c are connected by bypasses 60 to liquid channels 28 that differ from each other. Moreover, the first supply manifold 40a is connected by the first bypass 61 one-on-one to the second return manifold 50b, the second supply manifold 40b is connected by the third bypass 63 one-on-one to the third return manifold 50c, and the third supply manifold 40c is connected by the second bypass 62 one-on-one to the first return manifold 50a. Hence, uniformity of flow rates of liquid in the manifolds 40, 50 can be achieved, while crosstalk is reduced.

<First Modification>

In a liquid discharge apparatus 10 according to a first modification, in the above-described embodiment, cross-sectional area through which liquid passes, of the second bypass 62 is larger than in the first bypass 61 and the third bypass 63. For example, cross-sectional area of the second bypass 62 is area orthogonal to a flow-through direction that liquid flows to the first return manifold 50a from the third supply manifold 40c. Cross-sectional area of the first bypass 61 is area orthogonal to a flow-through direction that liquid flows to the second return manifold 50b from the first supply manifold 40a. Cross-sectional area of the third bypass 63 is area orthogonal to a flow-through direction that liquid flows to the third return manifold 50c from the second supply manifold 40b.

In the example of FIGS. 4 and 5, cross-sectional area of the bypass 60 differs in its upper portion, middle portion, and lower portion. In such a case, fellow corresponding portions in the first bypass 61, the second bypass 62, and the third bypass 63 may be compared. In this case, cross-sectional area of the second upper portion 62a is larger than cross-sectional area of the first upper portion 61a and cross-sectional area of the third upper portion 63a. Cross-sectional area of the second middle portion 62b is larger than cross-sectional area of the first middle portion 61b and cross-sectional area of the third middle portion 63b. Cross-sectional area of the second lower portion 62c is larger than cross-sectional area of the first lower portion 61c and cross-sectional area of the third lower portion 63c. Now, for example, cross-sectional area of the upper portions 61a, 62a, 63a is cross-sectional area orthogonal to the front-rear

direction, cross-sectional area of the middle portions **61b**, **62b**, **63b** is cross-sectional area orthogonal to the up-down direction, and cross-sectional area of the lower portions **61c**, **62c**, **63c** is cross-sectional area orthogonal to the front-rear direction.

If length along a flow-through direction in the second bypass **62** is longer than in the first bypass **61** and the third bypass **63**, then channel resistance in the second bypass **62** will become larger than in the first bypass **61** and the third bypass **63**. In contrast, cross-sectional area with respect to a direction that liquid flows through the second bypass **62** is larger than in the first bypass **61** and the third bypass **63**. As a result, channel resistance in the second bypass **62** will become smaller than in the first bypass **61** and the third bypass **63**. Hence, in the first bypass **61**, the second bypass **62**, and the third bypass **63**, channel resistances can be made equal to each other or have their differences with each other reduced to no more than a designated value, and flowrates can be made uniform with each other. For example, in the case of a viscosity region of liquid such as ink being not less than 2 (mPa·s) and not more than 10 (mPa·s), channel resistance of the bypass **60** will be about not less than 200 (kPa/(cc/s)) and not more than 2000 (kPa/(cc/s)).

Note that the bypass **60** may have each of cross-sectional areas of its upper portion, middle portion, and lower portion equal to each other, and may have said cross-sectional areas fixed. Moreover, regarding at least one portion from among the upper portion, the middle portion, and the lower portion, cross-sectional area may be larger in the second bypass **62** than in the first bypass **61** and the third bypass **63**, whereas for the other portions, cross-sectional area in the second bypass **62** may be the same as in the first bypass **61** and the third bypass **63**.

<Second Modification>

In a liquid discharge apparatus **10** according to a second modification, in the above-described embodiment and first modification, the supply manifold **40** and return manifold **50** extend in the left-right direction. A dimension in the up-down direction of the second bypass **62** is larger than in the first bypass **61** and the third bypass **63**.

For example, as depicted in FIG. 6A, the first upper portion **61a** of the first bypass **61** and third upper portion **63a** of the third bypass **63** are formed in the second channel plate **25b**. In contrast, as depicted in FIG. 6B, the second upper portion **62a** of the second bypass **62** is formed in the first channel plate **25a** and the second channel plate **25b**. Therefore, in the up-down direction, dimensions of the first upper portion **61a** and third upper portion **63a** are equal to a dimension **hb** of the second channel plate **25b**, whereas a dimension of the second upper portion **62a** is equal to the sum of a dimension **ha** of the first channel plate **25a** and the dimension **hb** of the second channel plate **25b**. Hence, the dimension of the second upper portion **62a** is larger than the dimensions of the first upper portion **61a** and third upper portion **63a**.

Moreover, as a separate example, as depicted in FIG. 6C, the second upper portion **62a** of the second bypass **62** is formed in the first channel plate **25a**, and its second middle portion **62b** is formed in the second channel plate **25b** and third channel plate **25c**. In this case, in the up-down direction, the dimensions of the first upper portion **61a** and third upper portion **63a** are equal to the dimension **hb** of the second channel plate **25b**, and the dimension of the second upper portion **62a** is equal to the dimension **ha** of the first channel plate **25a**. Now, the dimension **ha** of the first channel plate **25a** is larger than the dimension **hb** of the second channel plate **25b**. Therefore, in the up-down direction, the

dimension of the second upper portion **62a** is larger than the dimensions of the first upper portion **61a** and third upper portion **63a**.

In a cross-section of the upper portion orthogonal to the front-rear direction, a dimension in the up-down direction is smaller than a dimension in the left-right direction, for example. In this case, flow-through resistance of liquid along the front-rear direction can be kept smaller by increasing the dimension in the up-down direction than by increasing the dimension in the left-right direction. Hence, in the up-down direction, the dimension of the second upper portion **62a** is made larger than the dimensions of the first upper portion **61a** and third upper portion **63a**. As a result, even if length along a flow-through direction of liquid is longer in the second bypass **62** than in the first bypass **61** and third bypass **63**, channel resistance of the second bypass **62** can be kept small, and uniformity of flowrate in the first bypass **61**, second bypass **62**, and third bypass **63** can be achieved.

Note that as in the above-described examples of FIGS. 6B and 6C, the dimension in the up-down direction has been made larger in the second bypass **62** than in the first bypass **61** and third bypass **63**, for one portion from among the upper portion, middle portion, and lower portion. However, dimensions of the whole of the second bypass **62** may be made larger than in the first bypass **61** and third bypass **63**.

<Third Modification>

In a liquid discharge apparatus **10** according to a third modification, in the above-described embodiment and the first and second modifications, the supply manifold **40** and return manifold **50** extend in the left-right direction. The first individual channel **30a** included in the first liquid channel **28a** is located further to one side in the left-right direction than the first bypass **61**. The second individual channel **30b** included in the second liquid channel **28b** is located further to one side in the left-right direction than the third bypass **63**. The second bypass **62** is located further to the other side in the left-right direction than both the first bypass **61** and the third bypass **63**.

In the example of FIG. 3, the first individual channel **30a**, second individual channel **30b**, and third individual channel **30c** are disposed further to the right than the first bypass **61** and third bypass **63**, in the left-right direction. The second bypass **62** is disposed further to the left than the first bypass **61** and third bypass **63**, in the left-right direction. As a result, as depicted in FIG. 4, the first upper portion **61a**, second upper portion **62a**, and third upper portion **63a** are formed in the same second channel plate **25b** as each other. Therefore, increase in size of the head **20** in the up-down direction and increase in the number of components can be suppressed.

<Fourth Modification>

In a liquid discharge apparatus **10** according to a fourth modification, in the above-described embodiment and the first and second modifications, the supply manifold **40** and return manifold **50** extend in the left-right direction. The first individual channel **30a** included in the first liquid channel **28a** is located further to one side in the left-right direction than the first bypass **61**. The second individual channel **30b** included in the second liquid channel **28b** is located further to one side in the left-right direction than the third bypass **63**. The second bypass **62** is located between the first individual channel **30a** included in the first liquid channel **28a** and first bypass **61** and between the second individual channel **30b** included in the second liquid channel **28b** and third bypass **63**, in the left-right direction.

11

In the example of FIGS. 7 and 8, the first individual channel 30a, second individual channel 30b, and third individual channel 30c are disposed further to the right than the second bypass 62, in the left-right direction. The first bypass 61 and third bypass 63 are disposed further to the left than the second bypass 62, in the left-right direction. As a result, dimensions in the left-right direction of the third supply manifold 40c and first return manifold 50a connected to the second bypass 62 are shorter than in the first supply manifold 40a and second return manifold 50b connected to the first bypass 61 and in the second supply manifold 40b and third return manifold 50c connected to the third bypass 63. As a result, even if the second bypass 62 is longer than the first bypass 61 and third bypass 63, the third supply manifold 40c and first return manifold 50a will be shorter than the other manifolds. Hence, uniformity of flowrate in the supply manifolds 40 and return manifolds 50 can be achieved.

<Fifth Modification>

A liquid discharge apparatus 10 according to a fifth modification, in the above-described embodiment and the first to fourth modifications, comprises the drive element 23 that applies to liquid of the individual channel 30 a discharge pressure discharging the liquid from the nozzle 31. The supply manifold 40 and return manifold 50 extend in the left-right direction. The drive element 23, the supply manifold 40, and the return manifold 50 are disposed in this order in the up-down direction. The bypass 60 is disposed in the same position as the supply manifold 40 in the up-down direction, or in a position closer to the supply manifold 40 than to the return manifold 50 in the up-down direction.

Specifically, in the example of FIGS. 4 and 5, the upper portions 61a, 62a, 63a were formed in the second channel plate 25b. In contrast, in the example of FIGS. 9, 10A and 10B, the upper portions 61a, 62a, 63a are each formed in the first channel plate 25a. In this case, the channel forming body 22 does not include the second channel plate 25b. However, the upper portions 61a, 62a, 63a may be formed in the first channel plate 25a and the second channel plate 25b. Alternatively, the middle portions 61b, 62b, 63b may be formed in the second channel plate 25b and the third channel plate 25c. In this case, the channel forming body 22 does not include the second channel plate 25b.

The first upper portion 61a of the first bypass 61, which penetrates the first channel plate 25a in the up-down direction, extends frontwards from the first supply manifold 40a. A rear end of the first upper portion 61a is connected to the outflow port 42 at the front end of the first supply manifold 40a. The second upper portion 62a of the second bypass 62, which penetrates the first channel plate 25a in the up-down direction, extends rearwards from the third supply manifold 40c. A front end of the second upper portion 62a is connected to the outflow port 42 at the rear end of the third supply manifold 40c. The third upper portion 63a of the third bypass 63, which penetrates the first channel plate 25a in the up-down direction, extends frontwards from the second supply manifold 40b. A rear end of the third upper portion 63a is connected to the outflow port 42 at the front end of the second supply manifold 40b.

In this way, the bypass 60 is disposed in the same position as the supply manifold 40 in the up-down direction, or in a position closer to the supply manifold 40 than to the return manifold 50 in the up-down direction. The drive element 23 is closer to the supply manifold 40 than to the return manifold 50 in the up-down direction. Therefore, the bypass 60 is close to the drive element 23, the drive element 23 can

12

be cooled by liquid flowing along the bypass 60, and thermal degradation of the drive element 23 can be reduced.

Note that in the case described above, the first bypass 61, second bypass 62, and third bypass 63 are all formed in the first channel plate 25a. However, at least one bypass 60 of the first bypass 61, second bypass 62, and third bypass 63 may be formed in the first channel plate 25a, and the other bypasses 60 formed in the second channel plate 25b. Moreover, in the case described above, the bypass 60 was disposed in the same position in the up-down direction as the supply manifold 40. However, the bypass 60 may be disposed in a position closer to the supply manifold 40 than a midway point between the supply manifold 40 and return manifold 50, in the up-down direction.

<Sixth Modification>

A liquid discharge apparatus 10 according to a sixth modification, in the above-described embodiment and the first to fifth modifications, comprises a plurality of pairs of the channel units 27 configured including a plurality of the liquid channels 28 and the bypasses 60, as depicted in FIG. 11. The supply manifold 40 included in one pair of the channel units 27 is provided with a first supply port 41a supplied with liquid from a first tank 15a, and the supply manifold 40 included in another pair of the channel units 27 is provided with a second supply port 41b supplied with liquid from a second tank 15b. Now, the bypasses 60 included in the plurality of channel units 27 may have the same layout as each other. Note that in FIG. 11, the individual channel 30 is not illustrated.

In the example of FIG. 11, the channel unit 27 includes a first channel unit 27a and a second channel unit 27b that differs from the first channel unit 27a. Each of the channel units 27, that is, the first channel unit 27a and the second channel unit 27b includes a plurality of the liquid channels 28 and a plurality of the bypasses 60. The plurality of liquid channels 28 include the first liquid channel 28a, the second liquid channel 28b, and the third liquid channel 28c. The first liquid channel 28a includes the first supply manifold 40a and the first return manifold 50a. The second liquid channel 28b includes the second supply manifold 40b and the second return manifold 50b. The third liquid channel 28c includes the third supply manifold 40c and the third return manifold 50c.

The first supply port 41a of the first channel unit 27a includes the supply port 41 of the first supply manifold 40a, supply port 41 of the second supply manifold 40b, and supply port 41 of the third supply manifold 40c in the first channel unit 27a. The second supply port 41b of the second channel unit 27b includes the supply port 41 of the first supply manifold 40a, supply port 41 of the second supply manifold 40b, and supply port 41 of the third supply manifold 40c in the second channel unit 27b. A first return port 51a of the first channel unit 27a includes the return port 51 of the first return manifold 50a, return port 51 of the second return manifold 50b, and return port 51 of the third return manifold 50c in the first channel unit 27a. A second return port 51b of the second channel unit 27b includes the return port 51 of the first return manifold 50a, return port 51 of the second return manifold 50b, and return port 51 of the third return manifold 50c in the second channel unit 27b.

The sub-tank 15 includes the first sub-tank 15a and the second sub-tank 15b that differs from the first sub-tank 15a. The first sub-tank 15a and the second sub-tank 15b are connected to storage tanks 13 (FIG. 1) that differ from each other. The first sub-tank 15a is connected by the supply pipe 43 to the first supply port 41a of the first channel unit 27a, and is connected by the return pipe 44 to the first return port

51a of the first channel unit 27a. The second sub-tank 15b is connected by the supply pipe 43 to the second supply port 41b of the second channel unit 27b, and is connected by the return pipe 44 to the second return port 51b of the second channel unit 27b. As a result, the first channel unit 27a and second channel unit 27b through which liquids of storage tanks 13 differing from each other flow can be disposed in the same head 20 as each other. In this case, spacing of the nozzles 31 of the first channel unit 27a and nozzles 31 of the second channel unit 27b can be made smaller than when the first channel unit 27a and second channel unit 27b have been disposed in different heads 20 from each other. Hence, impact position of the liquid discharged by the nozzles 31 of the first channel unit 27a and impact position of the liquid discharged by the nozzles 31 of the second channel unit 27b can be adjusted with high precision.

The plurality of bypasses 60 include the first bypass 61, the second bypass 62, and the third bypass 63. Layout of the first bypass 61, second bypass 62, and third bypass 63 of the first channel unit 27a and layout of the first bypass 61, second bypass 62, and third bypass 63 of the second channel unit 27b are the same as each other. For example, in the examples of FIGS. 3 and 11, in the first channel unit 27a and second channel unit 27b, the first liquid channel 28a, the second liquid channel 28b, and the third liquid channel 28c are arranged from the rear in this order. Moreover, in the first channel unit 27a and second channel unit 27b, the first bypass 61 is connected to the first supply manifold 40a and second return manifold 50b, the second bypass 62 is connected to the third supply manifold 40c and first return manifold 50a, and the third bypass 63 is connected to the second supply manifold 40b and third return manifold 50c. Furthermore, in the first channel unit 27a and second channel unit 27b, the individual channel 30 is disposed further to the right than the first bypass 61 and third bypass 63, and the second bypass 62 is disposed further to the left than the first bypass 61 and third bypass 63. As a result, the same components can be utilized in manufacture of the first channel unit 27a and second channel unit 27b, and improvement in manufacturing efficiency and lowering of cost can be achieved.

<Other Modifications>

In the above-described embodiment and all of the modifications, the channel unit 27 included three liquid channels 28. However, the number of liquid channels 28 in the channel unit 27 is not limited to this, and it may include more than three of the liquid channels 28. For example, as depicted in FIG. 12, the channel unit 27 includes n liquid channels 28. In this case, the channel unit 27 includes n bypasses 60. Of the n bypasses 60, (n-1) of the bypasses 60 are connected to the following supply manifold 40 and prior return manifold 50, of fellow mutually adjacent liquid channels 28, for example.

Among the n bypasses 60, the second bypass 62 being the one remaining bypass 60 is connected to the first return manifold 50a of the rearmost first liquid channel 28a and nth supply manifold 40n of the frontmost nth liquid channel 28n, of the n liquid channels 28 arranged in the front-rear direction. In this way, the supply manifold 40 and return manifold 50 of a certain liquid channel 28 are connected by the bypasses 60 one-on-one to mutually differing liquid channels 28. Therefore, uniformity of flowrate of liquid in the manifolds 40, 50 can be achieved while crosstalk is reduced.

In the above-described embodiment and all of the modifications, in the channel unit 27, the first liquid channel 28a, second liquid channel 28b, and third liquid channel 28c were

arranged from rear to front. However, an arrangement direction of the liquid channels 28 is not limited to this. For example, as depicted in FIG. 13, in the channel unit 27, the first liquid channel 28a, second liquid channel 28b, and third liquid channel 28c may be arranged from front to rear. In this case too, the first supply manifold 40a is connected via the first bypass 61, only to the second return manifold 50b. The first return manifold 50a is connected via the second bypass 62, only to the third supply manifold 40c. As a result, the supply manifold 40 and return manifold 50 of a certain liquid channel 28 are connected by the bypasses 60 one-on-one to mutually differing liquid channels 28. Therefore, uniformity of flowrate of liquid in the manifolds 40, 50 can be achieved while crosstalk is reduced.

In the above-described embodiment and all of the modifications, a line head system was adopted for the liquid discharge apparatus 10. However, the system adopted is not limited to this system, and, for example, another system such as a serial head system may be adopted too. In this serial head system, the liquid discharge apparatus 10 comprises a carriage that is installed with the head 20 and moves the head 20 in the left-right direction. The liquid discharge apparatus 10 alternately executes a recording operation to discharge liquid from the head 20 while moving the carriage and a conveying operation to convey the recorded medium A by the conveying device 17, and thereby executes print processing to print an image on the recorded medium A.

In the above-described embodiment and modifications, a system employing a piezoelectric element (a piezo system) was adopted for the head 20. However, the system adopted is not limited to this system. For example, a thermal system employing a heating element or an electrostatic system employing a conductive vibrating plate and electrodes may be adopted for the head 20.

The above-described embodiment and each of the modifications may be combined with each other unless mutually exclusive. Moreover, numerous improvements or other embodiments of the present teaching will be obvious to a person skilled in the art from the above description. Hence, the above description should be interpreted merely as an exemplification, and is provided with an object of teaching a person skilled in the art the best mode of carrying out the present teaching. Details of structure and/or function of the present teaching may be substantively changed in a range not departing from the spirit of the present teaching.

What is claimed is:

1. A liquid discharge apparatus comprising:
a plurality of liquid channels each including:
an individual channel having a nozzle;
a supply manifold connected to the individual channel
to supply liquid to the individual channel; and
a return manifold connected to the individual channel,
the liquid that has not been discharged from the
nozzle being flowed through the return manifold; and
a plurality of bypasses each connected to the supply
manifold and the return manifold to cause the liquid to
flow therethrough, wherein
the liquid channels include a first liquid channel, a second
liquid channel, and a third liquid channel arranged in a
first direction,
the supply manifold included in the first liquid channel is
connected only to the return manifold included in the
second liquid channel, via a first bypass included in the
bypasses,

15

the return manifold included in the first liquid channel is connected only to the supply manifold included in the third liquid channel, via a second bypass included in the bypasses, and

the supply manifold included in the second liquid channel is connected only to the return manifold included in the third liquid channel via a third bypass included in the bypasses.

2. The liquid discharge apparatus according to claim 1, wherein a cross-sectional area, of the second bypass, orthogonal to a flowing direction of the liquid is larger than the cross-sectional area, of the first bypass, orthogonal to the flowing direction and the cross-sectional area, of the third bypass, orthogonal to the flowing direction.

3. The liquid discharge apparatus according to claim 1, wherein

the supply manifold and the return manifold extend in a second direction intersecting with the first direction, and

a dimension, of the second bypass, in a third direction intersecting with the first direction and the second direction is larger than the dimension of the first bypass in the third direction and the dimension of the third bypass in the third direction.

4. The liquid discharge apparatus according to claim 1, wherein

the supply manifold and the return manifold extend in a second direction intersecting with the first direction, the individual channel included in the first liquid channel is located on one side in the second direction with respect to the first bypass, and the individual channel included in the second liquid channel is located on the one side in the second direction with respect to the third bypass, and

in the second direction, the second bypass is located between the first bypass and the individual channel included in the first liquid channel and between the third bypass and the individual channel included in the second liquid channel.

5. The liquid discharge apparatus according to claim 1, wherein

the supply manifold and the return manifold extend in a second direction intersecting with the first direction, the individual channel included in the first liquid channel is located on one side in the second direction with respect to the first bypass, and the individual channel included in the second liquid channel is located on the one side in the second direction with respect to the third bypass, and

the second bypass is located on the other side in the second direction with respect to both the first bypass and the third bypass.

6. The liquid discharge apparatus according to claim 1, further comprising a piezoelectric element configured to

16

apply, to the liquid of the individual channel, a discharge pressure for discharging the liquid from the nozzle, wherein

the supply manifold and the return manifold extend in a second direction intersecting with the first direction, the piezoelectric element, the supply manifold, and the return manifold are disposed in this order in a third direction intersecting with the first direction and the second direction, and each bypass of the plurality of bypasses is disposed in the same position as the supply manifold in the third direction, or in a position closer to the supply manifold than to the return manifold in the third direction.

7. The liquid discharge apparatus according to claim 1, further comprising a plurality of channel units each including the liquid channels and the bypasses, wherein

the supply manifold included in one of the channel units is provided with a first supply port to which the liquid is supplied from a first tank, and the supply manifold included in another of the channel units is provided with a second supply port to which the liquid is supplied from a second tank.

8. The liquid discharge apparatus according to claim 7, wherein the bypasses included in the channel units respectively have the same layout as each other.

9. A liquid discharge apparatus comprising:
a plurality of liquid channels each including:
an individual channel having a nozzle;
a supply manifold connected to the individual channel to supply liquid to the individual channel; and
a return manifold connected to the individual channel, the liquid that has not been discharged from the nozzle being flowed through the return manifold; and
a plurality of bypasses each connected to the supply manifold and the return manifold to cause the liquid to flow therethrough, wherein

the liquid channels include a first liquid channel, a second liquid channel, and a third liquid channel arranged in a first direction,

the second liquid channel is arranged between the first liquid channel and the third liquid channel in the first direction, and

the supply manifold included in the third liquid channel is connected to the return manifold included in the first liquid channel, via a bypass included in the bypasses.

10. The liquid discharge apparatus according to claim 9, further comprising a sub tank configured to store the liquid, wherein

the supply manifold and the return manifold of each of the liquid channels are connected to the sub tank, the liquid is supplied from the sub tank to the supply manifold of each of the liquid channels, and the liquid is returned from the return manifold of each of the liquid channels to the sub tank.
